UNITED STATES PATENT OFFICE.

MARK VANDEWART, OF NEW YORK, N. Y.

DESIGN FOR A SCARF-PIN OR SIMILAR ARTICLE.

41,850.

Specification for Design.

Patented Oct. 24, 1911.

Application filed June 26, 1911. Serial No. 635,486. Term of patent 3½ years.

To all whom it may concern:

Be it known that I, MARK VANDEWART, a citizen of the United States, and a resident of the city, county, and State of New York, have invented a new, original, and ornamental Design for Scarf-Pins or Similar Articles, of which the following is a specification, reference being had to the accompanying drawing, forming part thereof.

The figure is a view in elevation of a scarf pin, showing my design.

I claim:—

The ornamental design for a scarf pin, or similar article, as shown.

In testimony whereof I affix my signature, in presence of two witnesses.

MARK VANDEWART.
